UNITED STATES PATENT OFFICE

2,171,696

METHOD FOR MAKING A TYPEWRITER
TYPE BAR REST

William F. Helmond, West Hartford, Conn., assignor to Underwood Elliott Fisher Company, New York, N. Y., a corporation of Delaware

Original application January 14, 1933, Serial No. 651,771, now Patent No. 2,036,272, dated April 7, 1936. Divided and this application January 22, 1936, Serial No. 60,204.

3 Claims. (Cl. 154—1)

This invention relates to an improved type-bar rest for a typewriting machine, and to its manufacture.

An object of the invention is to produce a highly efficient inexpensive structure. The padding material is of such character as to arrest the type-bar noiselessly, and without causing rebound, thereby avoiding clash with adjacent type-bars.

Asbestos, in fibrous condition, is used for padding material for the type-bar rest. In its ordinary pressed form, and particularly when fibers of shoddy character are used, asbestos would be liable to disintegrate into a powder under the type-bar blows. For the purpose of the invention, however, the asbestos is spun into yarn similar to that which is used for burner-wicking, the spinning process bringing out the collective strength of the fibers. Moreover long fibers are used, so that disintegration of the pad under the type-bar blows is successfully overcome. The spun yarn may be twisted into strands, which, in turn, may be twisted into a unitary cord which is strong and is easily inserted into the envelope. The cord when made of asbestos has the required dead cushioning property, and the asbestos fibers, being spun and twisted, are capable of resisting denting, packing and disintegration. The asbestos padding also has the capability of noiselessly arresting the type-bars without rebound.

The cord may be as thick as the required thickness of the filling and for making the filling broader than the diameter of the unitary cord, in order to produce the oblong sectioned pad, the invention effects doubling of the cord.

The improved padding material is provided with an envelope of woven fabric, of tubular form, and preferably provided with an external tangential flap, by means of which the pad is fastened to the usual curving support.

The invention quickly and inexpensively inserts and evenly compacts the cord into the long tubular envelope.

For distributing the force of the type-bar blow, it is desirable the pad presents a substantially broad surface against which the type-bars rest. The envelope is of oblong cross-section, and has moreover the external flap tangent to one flat side. The cord is compacted into such envelope uniformly throughout its length, so that, regardless of the twist in the cord, and which twist may tend to make the assemblage wind and twist, the filling conforms to the oblong section without creating any bulges, hollows or distortion in the pad.

By folding the cord end to end, and using the loop thus formed at one end as an eye, the doubled cord may be readily inserted into the envelope and drawn therethrough, making a tight fit, so as to compact the doubled cord.

The invention holds the envelope and distends one end of the tube for ready introduction of the cord. The envelope is kept smooth, and caused to assume, without distortion, the flat shape for which it is fashioned, while the doubled cord is being drawn in. Adjacent stretches of the cord are prevented from becoming twisted around one another, and the external longitudinal flap is kept tangent to a flat side of the pad. The doubled cord is supported and guided straight into the distended tube-opening.

The tight-fitting oblong sectioned envelope forces the adjacent stretches of the cord together and there is thus formed a self-contained, uniformly compact and undistorted pad-structure. Said structure may be subjected to a completing process by pressure, for the purpose of flattening the circular sectioned cord, so that the force of the type-bar blow is distributed over a large area of cushion. The asbestos filling is pliant enough to retain the flattened shape to which it is molded.

The invention therefore presents a simple, inexpensive method of building up a compact type-bar rest or pad having the desired properties.

This application is a division of my pending application No. 651,771, filed January 14, 1933, (now Patent No. 2,036,272, dated April 7, 1936).

Other features and advantages will hereinafter appear.

In the accompanying drawings,

Figure 1 is a view of the unitary cord before folding.

Figure 2 is a view showing the cord folded and a draw-string threaded through the looped end of the cord.

Figure 3 is a perspective view of the tubular fabric envelope, showing how one end thereof may be slit to form tabs used for distending the end of the tubular opening.

Figure 4 is a perspective view representing the cord as built up by spinning and twisting.

Figure 5 is a perspective view of the envelope and cord handling means employed to facilitate the insertion of the cord into the envelope.

Figure 6 is a view showing how the sides of the envelope are supported to keep the envelope smooth during insertion of the cord.

Figure 7 is a front-elevation diagram of the envelope in the holding means and represents the

cord as having been drawn into the envelope with the draw-string still attached.

Figure 8 is a side view showing envelope-holding jaws and a vise on which said jaws are mounted, the view indicating how said jaws receive the flap of the envelope preparatory to closing the vise.

Figure 9 is a perspective view showing details of spaced plates over which tabs of the tubular envelope are folded for distending the entrance to the tubular opening.

Figure 10 is a plan view of the pad, upon its removal from the holding means of Figure 5, with the cord fully inserted therein.

15 Figure 11 is a view similar to Figure 10, indicating the ends of the envelope closed over the ends of the inserted cord.

20 Figure 12 is a top-plan view indicating how the tabs at the end of the tubular envelope are folded over the aforesaid spaced plates to distend the entrance to the tube, the view being taken before a swingable clip is forced over the folded tabs.

Figure 13 is a top-plan view of the pad as mounted on its support.

25 Figure 14 is a cross-section through the pad and support, showing the pad before it is molded by the pressing process.

Figure 15 is a front elevation indicating how the pad is compressed between dies for flattening 30 the doubled cord.

Figure 16 is a cross-section of Figure 14, indicating how the pad is supported and located on one of the dies, and also indicating how the other die may be formed and how said die in descending 35 molds the pad.

Figure 17 is a fragmentary cross-section of the typewriter, showing a type-bar resting against the pad after being returned from printing against the platen.

40 In Figure 17, a type-bar 20 is one of the usual set arcuately arrayed in a segment 21, having a fulcrum-wire 22, about which the type-bars swing for co-operating with a platen 23. The type-bars are operable by key-actions represented by arm 24.

45 In their usual quick return from the platen, the type-bars are arrested by a novel pad 25 constructed as will be described, and fastened by screws 26 to the usual arcuate support 27, secured to the type-bar frame 28 by screws 29.

50 The novel pad includes an envelope 30 of woven fabric, Figure 3, fashioned into a tubular body-portion 31 to receive the novel filling which will be described presently. The sides of the tubular body 31 meet along a line 32 where they are joined as by sewing, knitting or weaving to form, externally of said body, a longitudinal flap 33 through which pass the screws for fastening the envelope to the support 27. The sides of the tubular body and the fastening thereof together 55 are so fashioned that when the envelope is filled, the resultant pad is of oblong cross-section with the flap 33 extending from one flat side at a tangent, so that when the flap is fastened to the aforesaid support, the body lies closely upon the latter as seen in Figure 14.

60 The filling or padding is cord made of long fiber asbestos. The long asbestos fibers are spun and twisted as in burner-wicking to bring out their collective strength and, for facilitating insertion 65 into the envelope 30, a unitary cord 35 of substantially circular section is formed. In order that the cord may be molded as will be described, the diameter thereof is made somewhat larger than the finished thickness of the padding. 70 Figure 4 illustrates the cord-structure in which

the yarns 36 are spun from the long asbestos fibers. The yarns 36 are twisted into strands 37, which, in turn, are twisted together to complete the cord. The process of spinning and twisting to form the cord may be substantially as practiced in the well-known art of cord-manufacture.

For making the padding wider than the thickness of the cord, the latter may be doubled. The doubling of the cord is preferably done by taking a piece of the cord 35, Figure 1, which is about twice the required length of the pad-filling, and folding said piece end to end, as indicated in Figure 2. A loop 38 thus formed at the end of the folded cord serves as an eye through which may be threaded a string 39 for drawing the cord in its doubled condition into the envelope 30.

Novel means for holding the envelope to facilitate insertion of the cord therein are arranged upon a vise, Figures 5 and 8, having a body 43 presenting a fixed jaw 44. The vise is mountable upon a work-bench, not shown. A movable jaw 45 of the vise has the usual shank 46 slidably fitting the body 43. The jaws are opened and closed by means of a screw 47, with which may co-operate a spring 48, Figure 8, for forcing the jaws apart when the screw, which has the usual cross-bar or handle, is turned for opening the vise.

The movable jaw 45 has fastened upon its clamping face an elongate bar 49 co-operative with another elongate bar 50, fastened upon the clamping face of the fixed jaw 44, said bars constituting special vise-jaws co-operating, as will be shown, for holding the envelope by gripping its flap 33 lengthwise. Above their flat gripping faces or portions, the bars form a channel 53 which serves to support the sides of the envelope in such manner that as the latter becomes filled by the drawing-in of the cord, the envelope is made to assume the oblong shape for which it is fashioned, with the flap 33 extending at a tangent from one flat side of said oblong shape, see Figure 6. Thus, as seen in Figures 6 and 7, the flap-gripping faces of the bars 49, 50 are at one side of the channel 53, the gripping face of the bar 49 being prolonged upwardly to form one side of the channel, and the opposite gripping face of bar 50 being topped by a ledge 54 forming the bottom of the channel.

For gaging the depth of insertion of the envelope-flap 33 between the gripping faces of bars 49 and 50, a stop may be formed as by the top of a tongue 56 extending outwardly from the flap-gripping face of the bar 50. The bar 49 has a groove 57 to receive the tongue 56, so that the top thereof extends under the gripping face of bar 49, see Figure 8. The groove 57 and tongue 56 may extend lengthwise of the bars 49, 50, and may co-operate to keep said bars in line with one another. A stop-pin 59, carried by shank 46 of the movable vise-jaw, prevents undue separation of the jaws, as will be evident from Figure 8. Screws 60 secure the bars 49, 50 to the vise-jaws.

For distending the tubular envelope-body 31 at one end for facilitating introduction of the cord, there is made in the envelope a slit 61, Figure 3, at the line of juncture of the flap 33 and the body 31 of the envelope. Another slit 62 is made at the top of the envelope. The slits are just deep enough to form tabs 63, which, when pulled laterally in opposite directions, serve to distend the entrance to the tubular body of the envelope.

In order that the envelope may be so distended while its flap is held by means of the vise-bars 49, 75

50, the latter are arranged at one end to present plates 65, 66, having toothed vertical edges 67, 68, over which the envelope-tabs 63 may be pulled, as indicated in Figure 12, to distend the entrance to the tubular part of the envelope. The plates 65, 66 are fastened respectively to bars 50 and 49 in such wise that their inner faces are flush with the sides of the channel 53 formed by said bars, the plates being fastened by screws 69.

For supporting the doubled asbestos cord 35 in folded condition and in line with the distended envelope-entrance, the bar 50 has fastened thereto, by screws 71, an arm 72 arranged to support beyond the entrance to the tubular envelope a U-shaped trough 73 into which the doubled cord may be snugly laid on edge, see Figure 5, the trough 73 being fastened to said arm 72. The trough supports the cord squarely in line with the distended entrance to the tubular envelope, and, before the cord is laid into said trough, the draw-string 39 may be threaded through the eye to the loop 38.

Prior to the laying of the cord into the trough 73, there may be inserted by way of the distended tubular opening of the envelope, a rod 76, long enough to reach beyond the far ends of the bars 49, 50, when a hook 77 of said rod extends beyond the distended envelope-entrance. With the rod 76 so inserted the draw-string 39 is caught over the hook 77 as shown in Figure 5, and the hook may then be drawn through the envelope to pull the draw-string through, the latter being preferably pulled through first before the cord is introduced into the envelope. The draw-string 5 having been pulled through, it is grasped and the cord, in turn, is pulled through until its trailing end reaches just within the slit part 0 of the envelope, as indicated in Figure 10. The doubled length of the cord and the length of the envelope are such that when the cord is thus drawn in, the loop-end of the doubled cord also falls within the envelope, as indicated in Figure 10. When the cord is in place within the envelope the draw-string 39 is simply pulled out 3 of the loop 38 and removed.

The envelope-tabs 63 may be held over the plates 65, 66, by which they are distended, by means of a U-shaped spring-clip 85, pivoted to the arm 72 at 86, and having upwardly-extending arms 87 which spring over the outer faces of the plates 65, 66, to pinch the tabs 63, when the clip is swung to the Figure 5 position. For release of the envelope-tabs 63, the clip 85 may be swung to the Figure 9 position.

15 The envelope 38 may be of such length that after the doubled cord is inserted, the envelope-ends may be trimmed square as along the dot-and-dash lines 89, Figure 10, and the ends may then be closed upon the ends of the inserted 20 doubled cord by metallic clips 90, formed to pinch the sides of the envelope together, as indicated in Figure 11.

The envelope is made tight fitting over the doubled cord inserted therein, the illustrated envelope and cord handling means making it possible, nevertheless, to easily insert the doubled cord into the envelope. The resultant type-bar rest 25 is compact, and when fastened to the arcuate support 27 has the shape seen in Figure 14. For flattening the tops of the cord, the assembled pad and filling are pressed preferably after being secured to said arcuate support 27. For this purpose the support 27, with the pad thereon, is laid upon a lower die 95, conforming 25 in shape to the support, having gages 96 and 97

for locating the support transversely, so that the pad on said support may align with an upper die 93, whose sides are flanged, as at 98, Figure 16, to mold the pad at its edges. Guide-pins 100, Figure 15, keep the upper and lower dies in alignment. The upper and lower dies are forced together to compress the pad, as illustrated in Figure 16, so that the top of the inserted cord is flattened to present a large area for distributing the force of the type-bar blows. The gage 96 is 10 in the form of a central arm shaped as shown and fastened to the front of die 95 by screws 101. The gage 97 may be pins driven into the concave face of the lower die as seen in Figure 15.

15 The method of constructing the novel pad and 15 the use of the herein-described means are as follows: The tubular envelope fabric is cut to a length sufficient to permit slitting one end and trimming both ends as indicated in Figure 10. The vise is opened and the flap of the envelope is 20 inserted between the bars 49, 50, so that it touches the top of the tongue 56 as in Figure 8. In this position the line 32 of the envelope where the flap begins is gaged slightly above the ledge 54 which forms the bottom of the channel 53.

25 The vise is now closed upon the envelope-flap and the tabs 63 of the envelope are pulled apart and folded over the toothed edges 67, 68 of plates 65, 66, as indicated in Figure 12, to distend the entrance to the envelope. The spring-clip 85 is 30 then forced over the tabs to hold the latter. The rod 76 is then inserted by way of the distended opening into the envelope with the hook 77 projecting slightly beyond the distended opening.

35 The asbestos cord 35 is pre-cut to about double the length of the required filling as in Figure 1, so that the folded cord of Figure 2 is of appropriate length. The doubled cord with the draw-string 39, threaded through its loop 38, as in Figure 2, is now laid edgewise into the U-shaped 40 trough 73 and the draw-string 39 is caught over the hook 77 of rod 76. The latter is now pulled through the envelope, and easily pulls the draw-string along with it so that the latter emerges from the far end of the envelope. The rod 76 is 45 now detached from the draw-string and removed and the operator then pulls upon the latter to draw the doubled cord into the envelope to the position seen in Figure 7. The draw-string may now be pulled out and removed and the spring-clip 85 may then be swung to release the filled envelope at the tabs 63. The filled envelope is 50 then removed from the apparatus upon opening the vise.

55 It is to be noted that during the insertion of the cord into the envelope, its sides are made to assume the oblong section for which the envelope is fashioned as may be seen in Figure 6. The ends of the envelope are now trimmed and by means of the clips 90 are closed upon the ends of the 60 doubled cord as illustrated in Figures 10 and 11. Upon removal from the vise after the insertion of the cord and the closing of the ends, the pad will have the shape seen in Figure 14.

Prior to pressing the pad in order to flatten its 65 top, the pad is fastened to the arcuate support 27 by means of the screws 26 which pass through the flap 33 of the envelope. The pad is now pressed as aforesaid between the dies 95 and 98 and is then ready for use in the typewriter as 70 indicated in Figure 17.

Variations may be resorted to within the scope of the invention, and portions of the improvements may be used without other.

Having thus described my invention, I claim: 75

1. The method of producing a typewriter type bar rest having a tubular fabric envelope and a fibrous filling evenly compacted therein, said method including preparing said filling as a fibrous twisted cord, folded double into an envelope-straining and oblong-rest-cross-section-forming pair of cords, the fold forming a loop at one end of said pair, demarking a longitudinal margin from a filling-receiving tubular part of the envelope as by a line of stitching, holding said envelope by mechanically clamping it entirely along said margin, holding the unclamped tubular part of the envelope against longitudinal pull relatively to the clamped margin by mechanically grasping and holding said tubular part at its mouth-forming end and concomitantly mechanically holding said end agape, pre-inserting a draw-string through said tubular part, and drawing and straining said cords into said tubular part by way of said mouth-forming end by means of said draw-string applied to said loop, said margin constituting a longitudinal flap appendant to the filled body of the envelope, said method further including confining the envelope oblongwise by applying rest-cross-section-forming mechanical buttresses along opposite sides of the envelope to constrain the cords, while they are being drawn in, to be disposed within the envelope, without wind or twist, in parallel stretches.
2. The method of producing a typewriter type bar rest having a tubular fabric envelope and a fibrous filling evenly compacted therein, said method including preparing said filling as a fibrous twisted cord, folded double into an envelope-straining and oblong-rest-cross-section-forming pair of cords, the fold forming a loop at one end of said pair, demarking a longitudinal margin from a filling-receiving tubular part of the envelope as by a line of stitching, holding said envelope by mechanically clamping it entirely along said margin, holding the unclamped tubular part of the envelope against longitudinal pull relatively to the clamped margin by mechanically grasping and holding said tubular part at its mouth-forming end and concomitantly mechanically holding said end agape, pre-inserting a draw-string through said tubular part, and drawing and straining said cords into said tubular part by way of said mouth-forming end by means of said draw-string applied to said loop, said margin constituting a longitudinal flap appendant to the filled body of the envelope, said method further including confining the envelope oblongwise by applying rest-cross-section-forming mechanical buttresses along opposite sides of the envelope to constrain the cords, while they are being drawn in, to be disposed within the envelope, without wind or twist, in parallel stretches.
3. The method of producing a typewriter type bar rest having a tubular fabric envelope and a fibrous filling evenly compacted therein, said method including preparing said filling as a fibrous twisted cord, folded double into an envelope-straining and oblong-rest-cross-section-forming pair of cords, the fold forming a loop at one end of said pair, demarking a longitudinal margin from a filling-receiving tubular part of the envelope as by a line of stitching, holding said envelope by mechanically clamping it entirely along said margin, holding the unclamped tubular part of the envelope against longitudinal pull relatively to the clamped margin by mechanically grasping and holding said tubular part at its mouth-forming end and concomitantly mechanically holding said end agape, said method further including slitting the opposite sides of said mouth end of the envelope just deep enough to form tabs grippable and tractable to hold and draw said end agape, pre-inserting a draw-string through said tubular part, and drawing and straining said cords into said tubular part by way of said mouth-forming end by means of said draw-string applied to said loop, said margin constituting a longitudinal flap appendant to the filled body of the envelope, said method further including confining the envelope oblongwise by applying rest-cross-section-forming mechanical buttresses along opposite sides of the envelope to constrain the cords, while they are being drawn in, to be disposed within the envelope, without wind or twist, in parallel stretches.

WILLIAM F. HELMOND.
